UNITED STATES PATENT OFFICE

2,299,891

TELEVISION TRANSMITTER

Gordon L. Fredendall, Westmont, N. J., assignor
to Radio Corporation of America, a corporation
of Delaware

Application October 24, 1940, Serial No. 362,494

6 Claims. (Cl. 178—7.2)

My invention relates to picture transmitters and particularly to transmitters of the type employing cathode ray pickup or transmitter tubes. Specifically, the invention relates to an improvement in the transmitter described and claimed in application Serial No. 362,547, filed on the same day as the present application, in the name of Alda V. Bedford, entitled "Television transmitter", and assigned to the Radio Corporation of America.

One of the major problems in television is that of obtaining a good picture signal to noise ratio without using too brilliant illumination on the subject being televised or without opening the lens aperture of the camera so wide that the depth of focus is too shallow. At times the problem is simply that of obtaining a usable picture signal under the lighting conditions available.

At one time it was the practice to make the resistance of the output resistor of a cathode ray pickup tube low enough to give the output circuit of this tube a flat frequency-response characteristic over the entire picture frequency range.

More recently the output resistor has been given a much higher value than indicated above whereby the picture signal components are held up to a good signal strength for the lower frequency components (up to about 100 kilocycles, for example). Generally the output resistor has a resistance of from 50,000 ohms to 200,000 ohms. The response characteristic is not flat, however, and falls off for the higher frequencies, this falling off of the characteristic being compensated for in a later stage. The circuit just described is usually referred to as the "high peaker" circuit and is covered by Bedford Patent 2,151,072, issued March 21, 1939, and assigned to the Radio Corporation of America.

An object of the present invention is to provide an improved transmitter circuit wherein the signal-to-noise ratio of a picture signal is improved by holding up or accentuating the picture signal amplitude in the region of the higher frequency components and later compensating for this accentuation.

Stated more broadly, an object of the invention is to provide an improved circuit for increasing the usable signal output of a picture transmitter tube.

A further object of my invention is to provide improved picture transmitter apparatus in which the signal-to-noise ratio of its output is improved and in which a simple and easily adjusted correcting or compensating network is employed.

In practicing the invention, an inductance coil is connected between the output electrode of the cathode ray transmitter tube and the control grid of the first amplifier whereby the output capacity of the transmitter tube and the input capacity of the amplifier are separated by the coil. This forms a low pass filter section. If conventional filter practice were followed, this filter section would be terminated in its surge impedance to prevent reflections. However, if this were done, the transmitter tube would work into an impedance too low for obtaining satisfactory signal-to-noise ratio, the impedance under these conditions being of the order of 3,000 ohms, for example, where the above-mentioned capacities are about 10 micro-microfarads each and where the inductance coil is adjusted for a cut-off frequency of about 4.5 megacycles. Because of this, the separation of two capacities in the pickup tube output circuit by means of an inductance coil formerly was considered undesirable.

In my improved transmitter, the conventional theory that major reflections at the end of a filter should not be allowed is discarded as taught by the above-mentioned Bedford copending application. Instead of terminating the filter section in its surge impedance of 3,000 ohms, for example, it is terminated in a very high resistance such as 100,000 ohms. This results in a tremendous peak in the picture signal in a certain region of the higher frequency components, the location of this peak depending upon the inductance value of the coil.

After a suitable amount of amplification, the picture signal is passed through a compensating circuit which has the proper characteristic to make the overall frequency response characteristic of the pickup tube and associated amplifier and compensating circuit substantially flat. This means, of course, that the compensating circuit is so designed that the picture signal components in the region of the above-mentioned peak are amplified less than the picture signal components of less amplitude. The result is that the noise, also, in the region of picture signal peak is amplified less whereby the overall signal-to-noise ratio is improved. The compensating circuit, in addition to providing amplitude correction, corrects for undesirable phase shift which is introduced by the above-mentioned inductance coil.

I have improved on the transmitter apparatus which is being claimed in the above-identified Bedford application by providing a correcting or

compensating network which is simple in design, but which, at the same time, gives the desired amplitude and phase compensation.

The invention will be better understood from the following description taken in connection with the accompanying drawing in which

Figure 1 is a circuit diagram of a television transmitter embodying my invention.

Figure 2 is a group of curves showing frequency response characteristics which are referred to in explaining the circuit of Fig. 1.

Figure 3 is a curve showing the square wave response of the circuit of Fig. 1 when my correcting network is omitted.

Figure 3a is a curve showing the square wave response of the circuit of Fig. 1 when my correcting network is included, and

Figure 4 illustrates another embodiment of my invention.

Referring to Fig. 1, the transmitter circuit comprises a cathode ray transmitter or pick-up tube 10 consisting of an evacuated envelope having therein an electron gun 11 for producing a beam of electrons, a second anode 12 and a mosaic 13 of light sensitive elements. In this particular type of pick-up tube a light image of the picture to be transmitted is projected upon the mosaic 13 by means of a suitable lens system, not shown. This causes an electrical image of the picture to be formed on the mosaic whereby picture signals representative of the conditions of light and shade in the picture are produced as the mosaic is scanned by the electron beam. The beam is caused to scan the mosaic by means of deflecting coils or plates, not shown. It will be understood that the invention is not limited to the specific type of pick-up tube 10, this type of tube being selected merely for the purpose of giving a specific example.

As stated in Bedford's above-mentioned "high peaker" patent, and as well known in the art at the present time, the mosaic 13 may be constructed in various ways. In all cases, however, it will be found that there is a substantial amount of capacity between the output electrode of the pick-up tube and ground, and that this is one of the limiting factors in obtaining a picture signal output of substantial amplitude at the higher frequency components of the picture signal. As explained in the said Bedford patent, this difficulty can be overcome to a certain extent by making the output resistance of the cathode ray tube much higher than the value required for a flat over-all response and compensating at a later point in the circuit for the resulting falling off of the signal amplitude at the higher frequency components.

In the transmitter of Fig. 1, in addition to giving the output resistor, shown at 16, a high resistance value as taught in the Bedford "high peaker" patent, an inductance coil L is connected between the output terminal of the cathode ray tube 10 and the control grid 17 of the first amplifier tube 18, whereby the output capacity of the cathode ray tube, indicated at C1, and the input capacity of the first amplifier tube, indicated at C2, are separated. It will be evident that now, instead of the sum of the capacities C1 and C2 appearing between the output terminal of the cathode ray tube and ground, the cathode ray tube feeds into a section of a low pass filter C1—L—C2.

In terminating this filter section C1—L—C2, however, conventional filter theory is not followed since filter theory would require that the

output resistor 16 (which terminates the filter section) have a resistance very much lower than the resistance actually employed. As previously indicated, filter theory would require that the filter section be terminated in a resistance of about 3,000 ohms, whereas, in practicing my invention, the filter section is terminated in a resistance of 100,000 or 200,000 ohms, for example.

As a result of the high resistance filter termination, the frequency response curve, taken at the control grid 17 of the first amplifier tube, is represented by the curve B1 in Fig. 2. It will be seen that this curve has a very high peak in the region of the high frequency components of the picture signal as a result of the high resistance termination of the filter section. It will be noted that curve B1 also has a large amplitude in the region of the lower frequency components of the picture signal as a result of the benefit derived from the high resistance of the output resistor 16 as described in the Bedford "high peaker" patent.

Perhaps it should be mentioned that the frequency response curves in the present application and those shown in the Bedford "high peaker" Patent No. 2,151,072 are drawn to scales which are so unlike that at first glance corresponding curves in the two cases do not look alike. In the "high peaker" patent, the curves are drawn up to one megacycle only and they are drawn to a logarithmic scale which "stretches out" the low frequency end of the scale. On the other hand, the frequency scale for the curves of Fig. 2 in the present application is linear and goes out to 5 megacycles.

In actual practice, it usually is desirable to accentuate the very low frequency components, components of the order of 60 or 100 cycles per second, for example, by means of a condenser 21 connected in series with the output resistor 16 and shunted by a resistor 22. The desired negative bias for the amplifier tube 18 may be provided by a biasing battery 23. In the illustration of Fig. 1, the condenser 21 and resistor 22 are shown short circuited by means of a switch 24 to make them ineffective. The curves in Fig. 2 are drawn for the condition of operation where the switch 24 is closed.

The use of the circuit 21—22 for accentuating the very low frequency components is described in Bedford Patent No. 2,200,073, issued May 7, 1940. Here again, the frequency scale for the curves in the patent is logarithmic, whereby the curve in the region of the lower frequencies is "stretched out." Since this accentuation of the signal occurs only in the general region of 100 cycles it is apparent that it could not very well be shown in Fig. 2 where the frequency scale is linear and covers 5 megacycles.

Still referring to Fig. 1, the amplifier tube 18 preferably is provided with the usual inductance coil 26 for holding up the high frequency response. The output of this amplifier is passed through one or more amplifier stages, such as the one including amplifier tube 27, and supplied to my improved correcting or compensating network indicated at 28. This network, which will be described in detail hereinafter, is designed to have the characteristic B2 of Fig. 2.

The operation of the circuit embodying my invention will now be more fully explained with reference to the curves in Fig. 2. The curve A1, which at the lower frequencies coincides with the curve B1, represents the frequency response characteristic of the circuit of Fig. 1 with the

coil L omitted. It will be evident that the use of the high resistance output resistor 16 has held up the picture signal output in the region below one megacycle. Following the teachings of Bedford Patent 2,151,072, a flat overall response, such as shown by the curve A3, would be obtained by means of a later compensating or "high peaker" stage having the frequency response characteristic shown by the curve A2.

With the coil L included in the circuit, as illustrated in Fig. 1, the frequency response measured at the control grid 17 of the first amplifier tube is that shown at the curve B1, there being a high peak in this curve in the region of the higher frequency components of the picture signal, this peaking being located at about 4 megacycles in the particular example illustrated.

As previously stated, the correcting or compensating network 28 has the frequency response characteristic shown at B2. The frequency response characteristic B2 is made such that the overall frequency response is flat, this flat overall frequency response being represented by the curve A3 previously referred to. It will be noted that the flat overall frequency response curve A3 is obtained if the ordinates of curves B1 and B2 are multiplied together rather than added together since the overall gain of two stages in cascade is obtained by multiplying rather than by adding the gains of the individual stages.

Referring now to the design of the correcting network 28, it comprises the network R7—C7—R5 connected across the output circuit of amplifier 27, the resistance of R7 being so high that the network puts substantially no load on the amplifier 27. The network R7—C7—R5 is one of the types of high peaker networks described in Bedford Patent 2,151,072 and, by itself, has essentially the frequency response characteristic A2 (Fig. 2).

The resistance of resistor R5 is low compared with that of resistor R7 whereby the amount of current flowing through the condenser C7 and through resistor R5 increases substantially as the signal frequency increases, this resulting in the rising characteristic A2 and in the rising portions of the curve B2.

The dip in the curve B2, occurring between three and four megacycles in the example shown, is produced by a series-resonant circuit comprising inductance coil L12, a condenser C12 and a resistor R12 connected across the resistor R5. The circuit L12—C12—R12 is series-resonant at the same frequency at which the resonant peak in the curve B1 appears, as will be evident from a comparison of curves B1 and B2. The desired amount of damping in the circuit L12—C12—R12 for properly shaping the curve B2 is introduced by adjusting the resistance value of R12.

It has been found that the above-described network 28 may be adjusted to compensate for the characteristic of the preceding part of the circuit so accurately that a picture of excellent quality is obtained. This means, of course, that the network compensates for both the amplitude and the phase distortion that has been introduced by the combination L—C1—C2.

The output circuit of the amplifier 27, across which the network 28 is connected, preferably includes the usual inductance coil 31 for holding up the amplifier high frequency response, a plate resistor 32, and a coupling condenser 33. More specifically, the amplifier stage 27 (without the compensating network 28) is designed to have a flat frequency response characteristic in the ex-

ample illustrated. The same is true for the amplifier stage 38.

It may be found desirable in some instances to connect a condenser C13 across the series-resonant circuit L12—C12—R12 by means of a switch 36. Calculations and tests show that this circuit will provide more perfect correction than can be obtained with condenser C13 omitted.

Some of the circuit constants for the specific apparatus shown in Fig. 1 are given below, by way of example, the capacity and inductance being given in micro-microfarads and microhenrys:

15 With switch 36 open:

C1=C2=10 mmf.
L=351 mu h.
Resistor 16=100,000 ohms
C7=6 mmf.
R7=330,000 ohms
R5=680 ohms
L12=25 mu h.
C12=70 mmf.
R12=12 ohms

20 25 With switch 36 closed:

L12=33 mu h.
C12=54 mmf.
C13=45 mmf.
R12=12 ohms

30 (Other constants unchanged)

It has been found that the circuit of Fig. 1 may be adjusted very easily to produce a picture of good quality. In adjusting the circuit, the series-resonant frequency of the circuit L12—C12 is made equal to the frequency of the peak response of the cathode ray output circuit, this being 3.8 megacycles in the example illustrated. The ratio of L12 to C12 is varied until the best compensation is obtained. Usually the adjustments may be made by observing a test pattern. The values of R7, C7 and R5 are determined by causing this portion of the circuit to compensate for the cathode ray tube output circuit when the coil L in that circuit is short-circuited, and when the series-resonant circuit L12—C12 is opened. As a final adjustment with all elements included in the circuit, the resistor R12 is adjusted so that the overall amplitude response of the complete circuit illustrated in Fig. 1 is flat.

The characteristic of the circuit of Fig. 1 with and without the correcting network 28 is further illustrated by Figs. 3 and 3a. Fig. 3 shows the square wave response of the circuit with the coil L but without the correcting network, while Fig. 3a shows the square wave response of the circuit after the undesirable transient response introduced by the coil L has been compensated for by means of the correcting network.

The great improvement that may be obtained in the signal-to-noise ratio by practicing my invention will be seen more clearly from the following considerations. The curves A2 and B2, respectively, indicate the actual amplification following the grid 17 of the first amplifier tube that is necessary in order to obtain the same picture signal output for the case where the inductance coil L is omitted as for the case where it is included in the circuit. Since most of the noise in the system generally originates in the first amplifier tube 18 (assuming the case where the output resistor 16 has large resistance), the relative noise obtained with my invention as compared with that obtained without my invention is shown by a comparison of the ordinates

of curve B2 and A2, respectively. Obviously, my invention causes a substantial reduction in noise in the picture signal since the curve B2 is much lower in amplitude than the curve A2 over a large portion of the upper frequency range.

The position of the peak of the curve B1 in the high frequency region may be shifted either toward the high end or toward the low end of the frequency band by changing the value of the inductance coil L. It may be preferable to have this peak located at a slightly different frequency than shown in Fig. 2 if maximum noise reduction is to be obtained.

It is usually desirable to operate the circuit of Fig. 1 with the switch 24 open whereby the previously described accentuation of the very low frequency components is obtained. It will be understood that, when so operated, there is provided at some later point in the circuit a complementary attenuating means such as a small coupling condenser, as described in Bedford Patent No. 2,200,073.

In Fig. 4 there is shown an embodiment of my invention in which a parallel resonant circuit is utilized in place of the series resonant circuit L12—C12 of Fig. 1. Like parts in Figs. 1 and 4 are indicated by the same reference characters. At Z1 there is indicated an impedance network, corresponding to R1—C1 of Fig. 1, which causes the current flowing through R5 to increase with increase in signal frequency. The network Z2 is connected in series with the lead supplying signal from R5 to the succeeding amplifier (not shown) for producing the desired dip in the curve B2. It comprises a parallel resonant circuit L14—C14 tuned to resonate at the frequency of the resonant peak in the curve B1. The resistor R14 may be the grid leak of the above-mentioned succeeding amplifier.

From the foregoing description, it will be apparent that various other modifications may be made in my invention without departing from the spirit and scope thereof.

I claim as my invention:

1. Electrical apparatus comprising a signal output device, said device having an output terminal which has unavoidable capacity to ground, an amplifier tube having a control electrode which has unavoidable capacity to ground, an inductance coil connecting said output terminal to said control electrode whereby said coil and said capacities form a filter section, a termination for said filter section comprising a resistor having such high resistance that said section is terminated in an impedance many times its surge impedance whereby the picture signal output appearing at said control electrode has a resonant peak in the region of its high frequency components, and a correcting network connected in cascade with said amplifier tube and designed to correct for amplitude and phase distortion introduced by said filter section, said correcting network comprising a resistor from across which the output signal is taken, means for causing the signal current flow through said last named re-

sistor to increase with increase in signal frequency, and a network connected across said last named resistor for decreasing the output voltage of the correcting network at the frequency of said resonant peak.

2. Picture transmitting apparatus comprising an electric discharge device for converting pictures into electrical signals, said device having an output terminal which has unavoidable capacity to ground, an amplifier tube having a control electrode which has unavoidable capacity to ground, an inductance coil connecting said output terminal to said control electrode whereby said coil and said capacities form a low pass filter section, a termination for said filter section comprising a resistor having such high resistance that said section is terminated in an impedance many times its surge impedance whereby the picture signal output appearing at said control electrode has a resonant peak in the region of its higher frequency components, and a correcting network connected in cascade with said amplifier tube and designed to correct for amplitude and phase distortion introduced by said filter section, said correcting network comprising a resistor from across which the output signal is taken, means for causing the signal current flow through said last named resistor to increase with increase in signal frequency, and a resonant circuit connected to said last named resistor and tuned to resonance substantially at the frequency of said resonant peak to reduce the amplitude of the signal appearing across said last named resistor at said frequency.

3. The invention according to claim 2 wherein the last named means comprises a resistor of comparatively high resistance in series with the last named resistor, and a condenser connected in parallel relation to said high resistance resistor.

4. The invention according to claim 2 wherein the said resonant circuit is a series resonant circuit connected in parallel with the last named resistor.

5. The invention according to claim 2 wherein the said resonant circuit is a parallel resonant circuit connected in series with an output lead from said last named resistor.

6. In picture transmitting apparatus, a correcting network for a picture transmitter tube output circuit which is in the form of a low pass filter section terminated by a resistor having much higher resistance than the surge impedance of said filter section, said correcting network being connected in cascade with said output circuit and comprising a resistor and a condenser connected in parallel with each other, a second resistor connected in series with said parallel combination, a series resonant circuit connected in parallel with said second resistor, means for impressing the signal to be corrected across said series combination of first resistor and second resistor, and means for taking the corrected signal from across said second resistor.

GORDON L. FREDENDALL
